Nelsor Dawson Design for Warpselvng
Patented April 10 1849

G. M.

Dec. 213

Peter Lawson Lowell Mass.
Letters Patent No 213 dated April 10th - 1849
The schedule referred to in these letters Patent 13 and
making part of the same

To all to whom these presents shall come, Be it known
that I Peter Lawson of Lowell in the County of Middlesex
and State of Massachusetts have invented or designed
a new pattern to be woven or printed on Carpeting &c
and that the following is a full, clear, and exact descrip-
tion of the principle or character which distinguishes
it from all other things before known, referred to being
had to the accompanying drawing numbered 767.

This design consists of a white shield (a) on a red
ground. The frame of the shield is formed of two re-
ctangular foliated pillars (b) with a peculiar curved arch
(c) connecting them, there being an irregular scroll or
leaf (d) thrown, of brown and yellow with red inter-
mingled; the bottom of the shield is enclosed by a
straight red bar (d) the ends of which are over-
hung with bunches of leaves & a sprig of oak leaves

2

Dec. 213

and becomes *f*, hairy, and an *i* from the scroll, the scroll being
the leaves being made to partly envelop a flower *i* with three
stamens projecting therefrom with leaves *l* extending over
one of the pillars *b* and a red flower *k* over the other, just
above, and partly concealing the stems of the leaves *e*.
Between the shields a brown vine *m* meanders over the
ruby ground, having connected with it blue and white
flowers and red roses, with green leaves.

Having thus, fully described my design and illustrated
the same by the accompanying drawing, I claim and
desire to secure the same by letters patent.
